CIRCUIT BREAKER

Ernst Eichenberger, Wettingen, Switzerland, assignor to Aktiengesellschaft Brown, Boveri & Cie, Baden, Switzerland, a joint-stock company

Application January 16, 1946, Serial No. 641,571
In Switzerland January 26, 1945

8. Claims. (Cl. 200—148)

1

This invention relates in general to circuit breakers and in particular to circuit breakers constructed for use in interrupting direct current power loads.

Generally speaking, arcs formed by separation of the contact elements of circuit breakers of conventional design when interrupting a direct current load are extinguished by extending the length of the arc until the voltage required to maintain it is greater than the line voltage of the direct current system in which the circuit breaker is connected. Various expedients have been devised for accomplishing this. In one arrangement, the circuit breakers have been provided with walls of metal or insulating material which are positioned transversely of the arc path, so that the arc can apply itself in wave form to the edges of these walls. The extension of the loop portion of the arc between such walls has also been aided by the use of pressure gas in order to improve its extinguishing characteristic. Furthermore, it has also been proposed to arrange metal parts in an arc extinguishing chamber of insulating material so that these parts are touched by the loops of the arc whereby heat is extracted from the arc and its extinguishing facilitated.

For use on alternating current circuits, circuit breakers have been disclosed which comprise at least one hollow, nozzle contact through which the arc, formed upon separation of the circuit breaker contacts, is blown with pressure gas. Such construction is quite satisfactory for breaking alternating current loads. Since the arc in the hollow contact is surrounded on all sides with the gas stream and cooled down greatly, and also since the space between the contacts is rapidly deionized by the flowing gas, the arc is extinguished as the current wave passes through zero and will not re-establish itself.

Circuit breakers of the latter type, however, are not suitable for use in interrupting direct current loads because, in a direct current system, the amplitude of the current and voltage is maintained at load values and hence does not possess a "zero" characteristic as in alternating current systems.

An object of this invention is to provide a novel and improved circuit breaker construction for use on circuits which carry direct current loads. In a preferred form, my improved circuit breaker includes a pair of contact elements, one of which is hollow, and the other being in the shape of a pin having an end portion which enters and normally rests against the lower end of the hollow contact to close a circuit therethrough. The two

2

contact elements are mounted so that one of them separates from the other when subjected to a blast of gas under pressure. An arc blowing chamber adjoins the hollow contact and the side wall thereof supports a plurality of metal pins which are arranged vertically one above the other. One of the circuit breaker contacts has connected to it an arc-receiving electrode which extends into the lower end of the blowing chamber. Upon separation of the circuit breaker contacts, one root of the arc formed thereby ascends this arc-receiving electrode and the other root of the arc is held by the other circuit breaker contact. The medial portion of the arc loop is blown up through the arc blowing chamber, climbing upwardly from pin to pin and thus lengthening until extinction takes place.

In the drawings which illustrate preferred embodiments of the invention, Fig. 1 is a vertical section showing a construction wherein two circuit breaker sections each embodying the invention are connected in series. Fig. 1a is a transverse section taken on line 1a—1a of Fig. 1. Fig. 2, also a vertical section shows another arrangement wherein a single gas conduit is used to feed gas to the contact sets of both circuit breaker sections.

Referring now to Fig. 1 of the drawing, a tank 1, having a flat top surface is provided, and is adapted to receive gas under pressure from pipe 2 and to supply the pressure gas to the circuit through a control valve 3. Two circuit breaker sections 4 and 4' embodying the invention are supported by tank 1.

Circuit breaker section 4 includes annular casting sections 6 and 7 separated by an annular insulating column 8 to constitute a contact chamber 9. The lower section 7 is bowl-shaped and the bottom thereof terminates in a flange 10 which rests upon an annular insulator 11, the latter being supported upon and in communication with the interior of tank 1 through the valve 3. One side of the direct current circuit to be broken is connected at terminal 12 to the lower section 7.

The contact structure of circuit breaker section 4, which is housed within chamber 9 includes a hollow contact element 13 which may be cylindrical, as shown, or tapered outwardly from the bottom, and a pin type contact element 14 cooperating therewith. The middle portion 15 of pin 14 has a diameter slightly larger than the inside diameter of the opening through hollow contact element 13; the bottom portion 16 of the pin contact 14 is tapered and the upper portion 17 thereof is shaped to rod form of a comparatively small

diameter to constitute an arc-receiving electrode of the circuit breaker.

Pin 14 is fixed in position by means of supporting ribs 18 which extend upwardly from the lower section 7 of contact chamber 9.

Contact element 13 is provided with a flange 20 at the bottom thereof. The upper section 6 of contact chamber 9 also carries an internal flange 21. A coil spring 22 inserted between the two flanges 20 and 21 urges the lower end of hollow contact element 13 into engagement with the enlarged medial portion 15 of contact pin 14.

Adjacent the upper or outlet side of the hollow contact 13 is a tubular housing 23 which may be cylindrical, as shown, or tapered outwardly from the bottom up, if desired. Housing 23 is made from insulating material and forms an arc blowing chamber for the arc. A plurality of pins 24 of conductive material are arranged in vertically spaced relation inside of the housing and are supported in the wall thereof, it being noted that these pins project through the wall on both sides.

Surrounding tubular housing 23 is another tubular housing 25 also of insulation material which is supported within an annular groove 26 formed at the top of the upper contact chamber portion 6. Supported by, and projecting through, the wall of housing 25 are a plurality of auxiliary pins 27 spaced vertically, there being a pin paired with and at the same level as each of the pins 24.

A metallic cap member or muffler 28 extends across the top of housings 23 and 25.

The component parts of the circuit breaker section 4' are constructed and arranged in the same manner as corresponding parts of circuit breaker section 4. Accordingly, corresponding parts of the two circuit breaker sections have been designated by corresponding reference numerals, but with primes added thereto, and no further description of circuit breaker section 4' is deemed necessary.

The two circuit breaker sections 4 and 4' are electrically connected in series. Hence metallic caps 28 and 28' are interconnected by conductor 30; corresponding sets of auxiliary pins 27 and 27' are interconnected by conductors 31; and the upper contact chamber sections 6, 6' are interconnected by conductor 32. The other side of the line adapted to be broken by the circuit breakers 4 and 4' is connected to terminal 12' on the lower control chamber section 7' of circuit breaker section 4'.

Operation of the two circuit breaker sections 4 and 4' shown in Fig. 1 is started by opening valves 3, and 3' which permit gas under pressure to flow up through the insulator sections 11, 11' into the contact chambers 9 and 9'. Here the gas pressure is applied to the undersides of the flanges 20, 20' on hollow contact elements 13 and 13', causing the latter to be lifted upwardly against the action of springs 22, 22' to break the electrical contact between the pins 14, 14' and their mated hollow contacts 13, 13'. The arcs formed at the two circuit breaking points are blown up through the hollow contacts 13, 13' under the action of the pressure gas and then extended to form arc loops. One end of each of the arc loops travels upwardly to the top of the electrodes 17, 17' which terminate inside of the housings 23, 23', and these end portions of the arcs are bathed on all sides by the pressure gas stream which forces the arcs into the blowing chambers.

The other end portions of the respective arcs are blown into the housings 25, 25', and are there extended upwardly to bring the medial portions

of the arc loops across the gap between the opposed ends of the lowermost sets of pins 24, 27 and 24', 27', respectively. Portions of the arc loops are thereby short-circuited and extinguished; and the arc loops are similarly transferred upwardly to succeeding sets of pins 24, 27 and 24', 27' by the pressure gas blast.

When current is eventually interrupted by the stretching of the arcs which spring from electrodes 17, 17', reignition is effectively prevented as the flow of pressure gas has completely deionized the spaces between the respective sets of circuit breaker contacts 13, 14 and 13', 14'.

A modified construction of a circuit breaker incorporating the invention is shown in Fig. 2. Here both circuit breaker sections 4a and 4b have a common contact housing, the lower bowl-like portion 1a of which is supported upon a single tubular insulator 11a that is in turn supported upon the tank 1a. The lower portion of the contact housing divides into two chambers 8a and 9b which include hollow contacts 13a, 13b and mating contact pins 14a, 14b.

The electrodes 17a and 17b of contact pins, 14a, 14b differ from the construction used in Fig. 1 in that the electrodes 17a, 17b terminate within and just below the top of the hollow contacts 13a, 13b.

In the Fig. 2 arrangement, additional arc-receiving electrodes 34a, 34b are supported upon the hollow contacts 13a, 13b and these electrodes are extended to a point within the arc blowing chambers formed by housings 23a, 23b. The line terminals 12a, 12b are carried by the housings 6a, 6b in this form of the invention. Operation of the circuit breakers shown in Fig. 2 is substantially the same as that of Fig. 1.

If desired, only one of the circuit breaker sections such as the section on the left in Fig. 1 need be utilized to interrupt a direct current load in which case the projections 27 must be interconnected among themselves and to the contact 13; however, connection of two circuit breaker sections in series is advantageous in that it breaks the arc gap into a greater number of sections which are more easily extinguished.

I claim:

1. In a pressure gas circuit breaker for interrupting a direct current load, a pair of contact elements, one of said elements being hollow, means supporting said contact elements for movement of at least one contact relative to the other to open a circuit therebetween under the action of pressure gas, an inner tubular casing of insulating material constituting an arc blowing chamber, the bottom of said casing being open and disposed adjacent said hollow contact, an arc-receiving electrode connected to at least one of said contact elements, said electrode being extended into the lower portion of said casing, a plurality of conductive pins spaced one above the other and extending through the wall of said casing, an outer tubular casing of insulating material surrounding said inner casing and through which pressure gas flows, and at least one arc attracting electrode located in the space between said inner and outer casings and carrying the potential of the other of said contact elements.

2. A circuit breaker as defined in claim 1 wherein a plurality of arc attracting electrodes are located in the space between the inner and outer casings, said electrodes being constituted by conductive pins secured in the wall of the outer casing, said pins being electrically connected with

each other and with the other of said contact elements.

3. A circuit breaker as defined in claim 1 characterized by the feature that said casing is cylindrical.

4. A circuit breaker as defined in claim 1 characterized by the feature that said supporting means for said contact elements include a spring normally urging said elements into engagement with each other but which is yieldable under the action of pressure gas to permit separation of said elements.

5. In a pressure gas operated circuit breaker system for use in interrupting direct current loads; a pair of circuit breakers; each said circuit breaker including a pair of contact elements, one of said elements being hollow, means supporting said contact elements for movement of one relative to the other under the action of gas pressure to open a circuit therebetween, an inner tubular casing of insulating material constituting an arc blowing chamber, the bottom of said casing being open and disposed adjacent said hollow contact element, an arc-receiving electrode connected to at least one of said contact elements, said electrode being extended into the lower portion of said casing, a plurality of metal pins, said pins being spaced one above the other in the wall of said casing, an outer tubular casing of insulating material surrounding said inner casing and through which pressure gas flows, and a plurality of vertically spaced pins extending through the wall of said outer casing; means connecting corresponding pins in the walls of the outer casings of the two circuit breakers; means connecting said breakers electrically in series; and means for actuating the contact elements of both said breakers simultaneously.

6. A circuit breaker system as defined in claim 5 and further including separate tubular insulator means for supporting each said circuit breaker, the interior of each said insulator means being in communication with the contact elements of its respectively associated circuit break-

er and adapted to pass pressure gas therethrough to said contact elements.

7. A circuit breaker as defined in claim 5 and further including a single tubular insulator supporting both said circuit breakers, the interior of said insulator being in communication with the contact elements of both said circuit breakers to pass pressure gas therethrough to said contact elements.

10 8. In a gas pressure operated circuit breaker system; a pair of circuit breakers; each said circuit breaker including a pair of contact elements, one of said elements being hollow, means supporting said contact elements for movement of one relative to the other under the action of gas pressure to open a circuit therebetween, a pair of concentric casings of insulating material constituting arc blowing chambers, the bottoms of said casings being open and disposed adjacent 15 said hollow contact element, an arc-receiving electrode connected to at least one of said contact elements, said electrode being extended into one of said casings, and a plurality of metal pins in the wall of each said casing, said pins being disposed one above the other and projecting through the walls of said casings at the same levels to form sets of auxiliary arc-electrodes; connections between corresponding pins in the outer casings of said breakers; means connecting the contact 20 elements of said breakers in series; and means for actuating the contact elements of both said breakers simultaneously.
